UNITED STATES PATENT OFFICE.

HENRY E. JACOBS, OF FOND DU LAC, WISCONSIN.

ELECTRIC TEMPERATURE-CONTROLLING DEVICE.

SPECIFICATION forming part of Letters Patent No. 363,644, dated May 24, 1887.

Application filed September 7, 1886. Serial No. 212,933. (No model.)

To all whom it may concern:

Be it known that I, HENRY E. JACOBS, a citizen of the United States, residing at Fond du Lac, in the county of Fond du Lac and State of Wisconsin, have invented certain new and useful Improvements in Electric Temperature-Controlling Devices; and I hereby declare the following to be a full, clear, and exact description of the same.

My present invention relates to an improvement upon devices of the nature of that for which I filed an application for Letters Patent of the United States, Serial No. 209,057, on the 26th day of July, 1886, it being my present object to provide simple and effective means for locking the valve device which controls the inlet and exhaust passages for the compressed air, serving to actuate the flexible receiver or diaphragm to open and close the main valve controlling the passage through which the temperature-affecting medium (hot or cold air, hot water, or steam) enters the apartment to be heated or cooled, the purpose of locking the valve device being to hold it in desired position with reference to the passage it controls after the circuit shall have been automatically opened by the lowering or raising of the temperature of the apartment.

My invention consists in the general construction of my improvement, and it also consists in certain details of construction and combinations of parts, all as hereinafter more fully set forth.

In the drawings, Figure 1 represents my device in elevation with the cover of the box removed to display its contents, and Figs. 2 and 3 are broken and partly sectional views of details.

A is a box, perfectly air-tight when the cover is on, preferably of insulating material, and provided with a tube, C, forming the inlet passage for compressed air supplied from an exterior source, (not shown,) with which the tube C is suitably connected, and with an exhaust-tube, B, which tubes B and C extend toward each other into the box, and are on the same plane, a space being left between them for the valve device, hereinafter described.

D is the flexible receiver, communicating from one end with the box A at an opening, r, therein, and connected at its opposite closed end with the main valve E by means of the

rod q, having pivoted to its extremity a lever, p, fulcrumed toward its center to an arm, o, extending from the shell of the valve E, and connected at its opposite end to the valve-stem, whereby the expansion of the receiver D closes the valve E, to prevent the passage through it into the apartment the temperature of which is to be affected of the proper agent for the purpose, and the collapse of the receiver opens the valve to permit the passage through it of such agent.

F and F' are electro-magnets suspended from one end within the box A, being preferably of the kind having their cores extended from their upper ends, or ends at which they are secured in position, adjacent to the exposed poles n n', as shown, to afford the poles m m', and thereby increase the attractive force of the magnets.

An armature, G, is provided for the magnet F, and extends across the pole n m from a shoe, I, pivotally supported to hang and oscillate between metal standards I', one of which only is shown, (and that in dotted lines to avoid obstructing other parts,) owing to the nature of the view selected to illustrate the device, and the shoe I carries at its lower end, to oscillate between the adjacent ends of the tubes B and C, the valve device K, comprising a short solid cylinder, l, having at opposite ends, preferably, rubber valves k and k', dovetailed into the ends of the cylinder l to enter the nozzles of the respectively adjacent tubes B and C and alternately close the exhaust and inlet passages. Extending from the upper end of the shoe I is a metal rod, I', having a head, I'', to make alternate contact, owing to the attraction by and release from the electro-magnets of the armatures, with the contact-points N and N' connected, respectively, with the electro-magnets by conductors x and x'.

H is the armature for the magnet F, provided with an extension or finger, H', at which the armature is pivotally supported in position, and which extends into contact with the adjacent side of the shoe I, slightly curved in an upward and backward direction, as shown.

Both armatures have a tendency to be maintained normally out of contact with their respective electro-magnets, produced by spiral springs h h', secured at one end to the same,

- to one side of the pivotal support of each, as shown, and at the opposite end to the box. Without the box A is a battery, L, having connected with one of its poles a thermostat, 5 M, as shown, or other suitable temperature-measuring instrument, which extends between contact-points g and g' , respectively connected by conductors f and f' through binding-posts f^2 with the electro-magnets F and F'. The 10 opposite pole of the battery L is connected, through a binding-post, e, with the metal standard I' by a conductor, e'; or, if the box is of metal, the conductor e' may be connected directly to the box.
- 15 The general purpose of the device being automatically to open and close the valve E, and thus permit or prevent the passage into an apartment of a suitable temperature-affecting medium by admitting to or exhausting from 20 the collapsible receiver D the power which actuates it to control the valve E, and the particular purpose of the locking detail of the device being to hold the valve mechanism which controls the inlet and exhaust passages 25 tightly against the passage C when moved into contact with the same, and without requiring the electro-motive force of the battery to be constantly exercised for the purpose, which would rapidly exhaust the battery, the manner 30 of operation will be understood from the following: The normal condition of the battery-circuits is open, being closed by the contact of the end of the thermostat—bent to make such contact by the effect of the temperature 35 within the apartment containing it, and the temperature of which it is desired to regulate—with a contact-point, g , or g' —if the first, g , the current passes from the battery by way of the thermostat through the magnet F, and 40 then by way of the contact-point N, rod I', and standard I', over the conductor e', back to the battery. As shown in Fig. 1 of the drawings, the device is represented by the full lines as having excited the electro-magnet F by contact 45 of the thermostat with the contact-point g , whereby the armature G was attracted from its position shown in dotted lines against the resistance of the spring h, being held there by the extension H' of the armature H, wedged 50 against the curved surface of the pivoted shoe (as shown by the full lines) by the downward strain of the spring h', to maintain the armature G in contact with the adjacent magnet F, or rather the valve device K in position to 55 close the passage C and open the passage B, after breaking of the circuit containing such magnet. When the effect of the temperature produced by the operation thus described (which has opened the exhaust-passage B and 60 closed the inlet-passage C) shall have caused the thermostat to close the circuit, including the magnet F', the armature H will be attracted against the resistance of the spring h' to its position shown by the dotted lines, thereby 65 releasing the shoe I from contact with the end of the extension H', and permitting the spring h to act on the armature G to move the valve

device K into position to open the inlet-passage C and close the exhaust-passage B. This breaking of a circuit occurs immediately after, and as a consequence of the attraction by a magnet of its armature, since the armature G and rod I', with its head I², are substantially in the form of a bell-crank lever, pivoted near the angle, whereby the attraction of the armature for closing the inlet-passage C throws the head I² against the contact-point N', where it is in position to form part of the circuit closed by contact of the thermostat with the contact-point g' , when the 80 change of temperature to the predetermined degree shall produce such action on the part of the thermostat, and, in like manner, when the armature H is attracted as a consequence of such contact of the thermostat with the point g' , the wedging effect of the extension H' upon the shoe I is removed, permitting the spring h to act and pull down the armature G, which moves the head I² on the rod I² against the contact-point N, or into position to continue the 85 circuit when closed to open the passage B and stop the passage C by contact of the thermostat with the point g , produced automatically by a predetermined degree of temperature.

It will thus be seen that whenever the armature G is attracted by the magnet F to produce stoppage of the inlet-passage C, the circuit is immediately broken; but the valve K is held or locked in its position to maintain closed the inlet-passage C by the extension H', raised to wedge itself against the shoe I by the downward pulling effect of the spring h' upon the armature H, and that as soon as the armature H is attracted by the magnet F' it releases the shoe I from the wedging effect of the extension H' by lowering the latter, thereby permitting the spring h to act by pulling downward the armature G, removing the valve device from the passage C and against the passage B, which is thus closed and held so by the spring h until the armature G is again attracted. In the one case, as it will be seen, the extension H' locks the valve device K against the tube C; in the other the spring h holds it against the tube B. While the springs h and h' form the preferred medium for their purpose, it is obvious that any other means may be employed that will produce the desired effect upon the armature to act in the manner described when uninfluenced by attraction of the magnets and released by the breaking of the circuits.

What I claim as new, and desire to secure by Letters Patent, is—

1. In an electric temperature-controlling device operating automatically by the opening and closing of the circuit through the medium of a heat-measuring instrument to open and close the inlet and exhaust passages for the power which actuates the valve E, the combination, with the electro-magnet F', of a valve device, K, an armature, H, maintained normally out of contact with its electro-magnet, and a finger, H', controlled by the armature

alternately to lock and release the valve device, substantially as and for the purpose set forth.

2. In an electric temperature-controlling device operating automatically by the opening and closing of the circuit through the medium of a heat-measuring instrument to open and close the inlet and exhaust passages for the power which actuates a valve, E, the combination, with the electro-magnets F and F', of a pivoted armature, G, maintained normally away from its electro-magnet, a valve device, K, connected with and controlled by the armature G, and extending between the said inlet and exhaust passages, and a pivoted armature, H, maintained normally away from its electro-magnet and extending toward the armature G to engage with the same, substantially as and for the purpose set forth.

20 3. In an electric temperature-controlling device operating automatically by the opening and closing of the circuit through the medium of a heat-measuring instrument to open and close the inlet and exhaust passages for the power which actuates a valve, E, the combination, with the electro-magnets F and F', of a pivoted shoe, I, carrying the armature G, maintained normally away from its electro-magnet, and a valve device, K, extending between the said inlet and exhaust passages, and a pivoted armature, H, maintained normally away from its electro-magnet, and provided with an extension, H', to engage with the shoe I, substantially as and for the purpose set forth.

35 4. In an electric temperature-controlling device operating automatically by the opening and closing of the circuit through the medium of a heat-measuring instrument to open and close the inlet and exhaust passages for the power which actuates a valve, E, the combination, with the electro-magnets F and F', of a pivoted shoe, I, curved on one surface and carrying an armature, G, held normally away from its electro-magnet by a spring, h, and a valve device, K, extending between the said inlet and exhaust passages, and a pivoted armature, H, held normally away from its electro-magnet by a spring, h', and provided with an extension, H', to engage with the curved surface of the shoe, substantially as and for the purpose set forth.

50 5. In an electric temperature-controlling device operating automatically by the opening and closing of the circuit through the medium of a heat-measuring instrument to open and close the inlet and exhaust passages for the power which actuates a valve, E, the combina-

tion of electro-magnets F and F', contact-points N and N', a pivoted armature, G, maintained normally away from its electro-magnet, 60 and having connected with it a contact making and breaking device, I² I³, to oscillate between the contact-points N and N', and a valve device, K, extending between the said inlet and exhaust passages and controlled by the armature 65 G, and a pivoted armature, H, maintained normally away from its electro-magnet and extending toward the armature G, to engage with the same, substantially as and for the purpose set forth.

70 6. In an electric temperature-controlling device operating automatically by the opening and closing of the circuit through the medium of a heat-measuring instrument to open and close the inlet and exhaust passages for the power which actuates a valve, E, the combination, with the electro-magnets F and F', contact-points N and N', a pivotal shoe, I, curved on one surface and carrying an armature, G, held normally away from its electro-magnet by a 80 spring, h, a contact making and breaking device, I² I³, to oscillate between the contact-points N and N', and a valve device, K, extending between the said inlet and exhaust passages, and a pivoted armature, H, held normally away from its electro-magnet by a spring, h', and provided with an extension, H', to engage with the curved surface of the shoe, substantially as and for the purpose set forth.

85 7. The combination of a box, A, having an opening, r, and containing electro-magnets F and F', tubes B and C, contact-points N and N', connected with the electro-magnets, standards I', supporting a pivotal shoe, I, carrying 95 an armature, G, connected with the box by a spring, h, a valve device, K, extending between the tubes B and C, and a contact making and breaking device, I² I³, to oscillate between the contact-points N N', and a pivoted armature, H, connected with the box by a spring, h', and provided with an extension, H', and a 100 battery, L, having a thermostat, M, connected with one pole and extending between contact-points g and g', connected with the electro-magnets, and having its opposite pole connected with a standard, I', the whole being constructed and arranged to operate substantially as described.
